UNITED STATES PATENT OFFICE

EDWARD J. VON PEIN, OF DAYTON, OHIO, ASSIGNOR, BY MESNE ASSIGNMENTS, TO THE NATIONAL CASH REGISTER COMPANY, OF DAYTON, OHIO, A CORPORATION OF MARYLAND

CASH REGISTER

Application filed September 25, 1922. Serial No. 590,373.

This invention relates to cash registers and is shown in connection with a machine of the type shown in applicant's Patent No. 1,593,203, granted July 20, 1926.

An object of this invention is the provision of means for operating a machine of the key-operated type from a source of power other than a key.

It is an object of this invention to so construct a key of the lever type that the amounts may be set up by a mere setting up operation, and the actual item entering operation may be performed by a source of power different from that of the key.

Specifically it is an object of this invention to construct a key of a plurality of members, a manipulative member and a member for connection with a key coupler, and to provide means operated by the manipulative member for causing the other member to be connected to the key coupler upon movement of the key coupler.

It is a further object of this invention to provide common driving means for separate mechanisms for total printing and for item registering and item printing; to provide means for controlling and effecting driving connections between said driving means and mechanisms; and to provide means for preventing a total printing operation after an operation of an item amount key.

With these and incidental objects in view, the invention consists in certain novel features of construction and combinations of parts the essential elements of which are set forth in appended claims and a preferred form or embodiment of which is hereinafter described with reference to the drawings which accompany and form part of this specification.

Figs. 1A and 1B comprise a plan view of the machine with parts omitted.

Fig. 2 is a transverse section through the machine looking toward the right.

Fig. 3 is a section through the totalizer.

Fig. 4 shows a universal shaft coupling involved in the turn-to-zero shaft.

Fig. 5 is a detail view showing the mechanism for releasing the motor and driving the key coupler during item entering operations.

Fig. 6 is a detail view showing the mechanism for releasing the machine and driving the printer during totalizing operations.

Fig. 7 is a side view of the printer.

Fig. 8 is a view showing the receipt issued by the machine.

Fig. 9 is a fragmentary portion of the detail strip.

Fig. 10 shows the driving connection between the key coupler and the cam shaft.

Fig. 11 is a detail view of part of the turn-to-zero mechanism.

Fig. 12 is a transverse section taken through the machine just inside of the printer frame, looking toward the left.

The machine includes a plurality of groups of amount keys, a totalizer, item entering and item printing mechanism, total printing mechanism, driving means, and keys for connecting the driving means with either the item entering and item printing mechanism or the total printing mechanism.

The keyboard comprises a plurality of groups of amount keys 20, an item control key 21 and a total control key 22. The amount keys 20 comprise two members, a front manipulative member 23, and a rear member 24 adapted to be coupled to a key coupler 31 in the usual manner. Both members are pivoted upon a rod mounted in the side frames of the machine. The item control and total control keys are mounted upon the ends of the rod projecting through said side frames.

In machines of this type, the members 23 and 24 generally heretofore have been made integral to drive the key coupler by depressing the keys. In this machine, the manipulative member 23, when depressed, functions to stretch a spring 25 (Fig. 2) secured to the frame and to a lever 26 pivoted to said member and provided with a pin 27 projecting over said member and in engagement therewith, and into the plane of a forward extension 28 of the member 24. As a manipulative member is depressed, spring pressure is exerted on the extension 28 of its corresponding rear key member to urge the rear end thereof toward the key coupler. As the key coupler is raised, the rear key member is also raised by the spring 25 a suf-

ficient distance to effect a coupling connection with the key coupler.

Actuator controllers 34, connected to the rear ends of the rear key members, are provided with notches 35 for engaging rods 36 carried by rocker frames controlling totalizer actuators 37, the notches 35 being located to transmit amounts of movement to the actuators proportionate to the number of units represented by the appropriate keys.

The actuators 37 and their respective rocker frames are operatively connected together as shown in the above mentioned patent.

The totalizer actuators 37 are normally in mesh with gears 38 which are connected with the item printing wheels 39 (Fig. 7) by nested tubes 40 (Fig. 12) to set up the amounts represented by the keys depressed.

The key coupler 31, before referred to, is pivotally mounted in the side frames and rests upon the rear ends of the key members 24. The right hand end of the key coupler (Fig. 10) carries a roller 41 which cooperates with a slot in a driving double rack 42 guided on a roller 43 mounted on the frame of the machine. The driving double rack is provided with opposing rack teeth adapted to be thrown into mesh alternately with a gear 44 on a cam shaft 45 to move the shaft in clockwise direction. The engagement of the rack teeth with the gear is effected and maintained by a spring 46, a spring pressed pawl 47, a flange 48 on the rack, and a flange 49 on the frame, operating in the usual manner.

The cam shaft 45 (Fig. 12) extends through the right hand side frame of the machine. A cam 50 fixed to this shaft cooperates with a spring pressed pivoted impression hammer supporting arm 51 curved to extend through an opening in the printer frame 52 (Fig. 7) into operative relation with the item type wheels 39. By means of this mechanism an impression is taken from the type wheels upon an issuing strip 55 during each item entering operation.

The right hand end of the key coupler is provided with a trunnion 56 (Fig. 7) extending through the printer frame. An arm 57 driven from the trunnion by means of a pin 58 secured to an arm 59 fixed on the trunnion inside of the printer frame, carries a spring drawn pawl 60 which cooperates with a ratchet (not shown) secured to a feed roller 51 secured on a shaft 62 for feeding the issuing strip between impressions. The arm 57 is held in place by a clip 53. A spring tensioned roller 63 holds the strip in frictional engagement with the feed roller. An inking ribbon 64 is provided and may be fed by a feed roller 65 which may conveniently be driven by a pawl and ratchet actuated by a link 54 connected to the arm 57 as usual.

The amounts represented by the keys depressed are entered in a totalizer mounted in

a frame 66 (Figs. 2 and 3) pivotally supported on trunnions 67 removably mounted in brackets projecting rearwardly from a front tie bar 68 secured to the side frames.

The totalizer elements include pinions 70 rigid with gear wheels 71 and ratchets 72, supported on a turn-to-zero shaft 73. The shaft is provided with a groove to cooperate with spring-pressed pawls on the totalizer elements to turn the totalizer to zero in the usual manner.

The totalizer pinions 70 are normally held disengaged from the actuators 37 by a cam 74, on the cam shaft 45, which cooperates with rollers 75 on a bifurcated lever 76 mounted on a pivot pin 77 on the totalizer frame but held rigid with the frame by a pin 78. When the key coupler is operated the cam is rotated clockwise and the totalizer pinions 70 are moved into mesh with the actuators 37.

For effecting transfers, each totalizer element is provided with a transfer trip projection 79 adapted to engage a projection on a trip pawl 80 to move the same out of supporting relation with respect to a transfer pawl 81 to permit the pawl 81 to move into engagement with the ratchet 72. This pawl 81 is supported on a transfer lever 82 which carries a roller 83 adapted to cooperate with a cam (not shown) on the cam shaft 45 during each operation of the machine to effect transfers in the usual manner.

The amount accumulated on the totalizer is ascertained by a printing operation. For this purpose, mechanism is provided for setting up total type wheels 85 (Fig. 7) in accordance with the amount in the totalizer. The totalizer is provided with stepped disks 86 (Fig. 2) rigid with gear wheels 87 mounted on a rod in the totalizer frame and meshing with the gears 71 rigid with the totalizer pinions 70.

The total type wheels 85 are located on the outside of the printer frame 52 and are suitably supported therein and in a supplemental frame 88. These wheels are connected by nested tubes 89 (Fig. 12) with gears 90 in mesh with segment-gears 91 rigid with other segment-gears 92 in mesh with segment-gears 93 connected by concentric tubes 94 with the legs of their respective yokes 95, (Fig. 2), the yokes each having an arm 96 extended to be moved into engagement with the steps on the disks 86 of the totalizer. The nested tubes 94 are supported by a rod mounted in the printer frame and in a bracket 97 mounted on the front tie bar 68. The steps on the stepped disks 86 are so located that the type wheels 85 will be set in accordance with the amount in the totalizer when the arms 96 of the yokes 95 are moved into contact therewith.

Integral with the segment-gears 92 (Fig. 12) are segment-gears 100 which mesh with segment-gear levers 101 having rear arms 102 connected by tension springs 103 to an operating lever 104. The springs are normally

restrained against moving the yokes 95 and total type wheels 85 by a yoke 105 connected by a link 106 to said operating lever 104. This lever is rocked first clockwise and then counter-clockwise by cams 107 secured on the driving shaft 108 driven by a motor as shown, or any other suitable means. As the operating lever 104 and yoke 105 are moved clockwise, the springs 103 are permitted to function to set up the total type wheels 85 in accordance with the amount in the totalizer in the manner described in the previously mentioned Von Pein Patent, No. 1,593,203, and also a Von Pein Patent, No. 1,555,534, dated September 29, 1925.

Impressions from the total type wheels are taken upon the issuing strip 55 before referred to, by a hammer 115 (Fig. 7) which carries a plurality of platens cooperating also with electros 116 and 117 to print the matter shown at the bottom and top of the receipt shown in Fig. 8. The hammer is connected to an arm 118 rigidly connected to an arm 119 carrying a roller at its lower end cooperating with a cam 120 fixed on the shaft 108.

For feeding the printed total amount on the issuing strip past a severing knife 125, a ratchet 126 (Fig. 12) is rigidly connected to the shaft 62 supporting the feed roller 61 and is driven by a pawl 127 carried by a rocker arm rigid with a pinion 128 in mesh with a segment-gear 129 driven from a roller 130 mounted on an extension of the operating lever 104.

It may also be desirable to print the totals on a detail strip fed over the top of the total wheels. A portion of this strip is shown in Fig. 9. The impression hammer arm 131 (Fig. 7) for effecting such printing may be driven by a link 132 connected to an arm 133 integral with the arm 119 before referred to. The detail strip may be fed by any suitable means operable during a total printing operation.

The means for returning the totalizer wheels to zero during a total printing operation includes as one of its elements, a segment-gear lever 137 (Fig. 11) connected by a short link 138 with the link 106. The segment-gear lever 137 meshes with a gear 139 secured to a shaft 140 which freely supports the segment-gears 91, 92 and 100 (Fig. 12). Secured to the shaft 140 on the left side of the printer frame is a segment-gear 141 (Fig. 12) which meshes with a gear 142 (see also Fig. 4) carrying a spring-pressed pawl 143 cooperating with a ratchet 144 rigid with a gear 145 in mesh with a gear 146. The gear 146 is mounted on a shaft 147 connected by a universal shaft coupling 148 with the turn-to-zero shaft 73 of the totalizer. By means of this mechanism, the totalizer is turned to zero during the latter part of the operation of the total printing mechanism.

The driving means preferably comprises a

motor 150 (Fig. 7) of the usual type in which the worm on the motor shaft drives a gear mounted on the clutch shaft 151. Mounted on the inner end of this shaft 151 is a gear 152 (Fig. 1B) in mesh with a gear 153 secured to a shaft 154 supported in the main right hand frame 155 and a bracket 156 secured to the motor frame.

Freely mounted on the shaft 154 is a cam disk 160 which cooperates with a roller 161 (Fig. 5) on a pivoted arm 162 connected by a link 163 with an arm 164 secured to the key coupler trunnion 56. The cam disk is provided with a female clutch member 165. Also freely mounted on the shaft 154 is a gear 166 in mesh with a gear 167 secured to the total printing drive shaft 108. The gear 166 is provided with a female clutch member 168.

The means for causing the cam disk 160 and gear 166 to rotate with the shaft 154 comprises the female clutch members on the disk 160 and gear 166 and a sleeve clutch member 169 (Figs. 1B and 6) slidably but non-rotatably mounted on the shaft 154 and provided with male clutch end portions to couple with either of said female clutch members 165 or 168. Normally the sleeve clutch member 169 is held in engagement with the clutch member 165 by means later referred to. In this position it drives the key coupler 31 for an itemizing operation. When it is desired to print a total accumulated on the totalizer, the sleeve clutch member 169 is moved to the right into engagement with the clutch member 168. This is effected by the total key 22, which will be described later.

The mechanism so far described is the same as that of the patent No. 1,593,203 referred to, except for the construction of the amount keys and the clutch mechanism for driving either the key coupler 31 or total printing mechanism from the same source of power.

Interlocking and control features

When the amount key members 23 are depressed, they set up a spring pressure against the rear key members 24 to select them for operation. The key members 23 are held depressed temporarily by spring-controlled latches 170 (Fig. 2) which snap over projections 171 on the members 23. There is one latch 170 for each group of keys. These latches 170 are supported by arms of levers 172 rotatably mounted on a rock shaft 173. The lower ends of these levers bear against pins 301 carried by arms 174 pinned to the rock shaft 173. The latches 170 are normally held in the position shown, by springs secured to the lower ends of levers 172 and to a rod carried by the frame of the machine. The shaft 173 extends through the right hand side frame. Inside of the frame it is provided with an arm 175 (Fig. 5) controlled by a key releasing lever 176 freely mounted on a control shaft 180, later

referred to. By means of the lever 176, depressed keys may be released before an entry of items is effected to enable the operator to make corrections in the amount set up.

5 The arm 175 (Figs. 2 and 5) is provided with a pin 302 extending into a slot 303 in a link 177 lying inside of the right hand frame. This link is connected with the link 163 by a pin 304 extending through a slot 305 in the frame. By this mechanism the temporary locking members 170 are released at the beginning of an item entering operation of the machine. The elongated slot 303 in the link 177 permits an operation of the lever 176 to release the depressed keys for correction without affecting the key coupler.

20 The motor 150 and the controlling stops and switch are of the same construction as those shown in the Von Pein Patent No. 1,593,203, and in Letters Patent of the United States to Kettering and Chryst, No. 1,144,418, granted June 29, 1915. A lock lever 184 (Fig. 6) similar to the lock lever 83 in said Kettering and Chryst patent releases the 25 motor, when moved counter-clockwise by a spring 185 and arrests the motor when moved clockwise by a cam 186 rotatable with the shaft 154.

30 The spring 185 is connected to the frame and to a slidably mounted link 187 connected to the lock lever 184. The link 187 is normally held in the position shown in Fig. 6 by a spring actuated catch 188 engaging a 35 stud 189 on the frame of the machine. An arm 190, also spring-actuated, is provided with a lip 191 in engagement with the end of the hook portion of the catch 188. A catch arm 192 slidably mounted on a stud 193 on the frame is provided with a laterally directed fin 194 in alignment with the lip 191. This trip arm is also provided with a latching shoulder 195 to cooperate with the stud 189. When the trip arm 192 is moved downwardly, the catch 188 is released and the lock lever 184 is moved to releasing position. When the lock lever is returned to locking position, the parts move back to the positions shown in Fig. 6. A tension spring 196 holds the trip arm against the stud 189. All of this 45 mechanism is substantially identical with that shown in the Patent No. 1,593,203 referred to.

50 The releasing mechanism described may be controlled from either the item control key 21 or the total control key 22. The control shaft 180 is mounted in the side frames of the machine. Adjacent to its left end, it carries a rigidly fixed arm 200 (Fig. 5) provided with a pin 201 extending under a bearing edge 202 on the item control key 21. The key 21 and the arm 200 are held in their 55 home positions by springs 203 and 204 respectively.

60 Secured to the control shaft 180 adjacent to the right hand side frame of the machine

is an arm 205 (Figs 2 and 6) which carries a pin 206 projecting through a plate 207 to which the trip member 192 is pivoted at 208 the plate 207 being slotted as shown to receive the stud 193 by which the trip arm 192 is guided. The total control key 22 (Fig. 6) carries a pin 209 for engagement with the plate 207 from which it is spaced when in its home position. The key 22 is normally held in home position by a spring 210 connected to a long stud 211 on the key, and to the frame.

65 When the item control key 21 or the total control key 22 is depressed, the control shaft 180 is rocked and the plate 207 is lowered to move the trip arm 192 downwardly to release the motor. When the motor releasing mechanism is returned to home position, the 70 springs 203, 204 and 210 return the control shaft and item and total keys to home positions.

75 The clutch sleeve 169 before described (Figs. 1B and 6) is controlled from the total control key 22, which is normally held in home position by the spring 210. The key is provided with an arm 215 connected by a link 216 with an extension 217 on a yoke 218 whose side members are mounted for rocking movement on the sleeve clutch member 169. The yoke 218 is held in place by a sleeve 219 located between the side members of the yoke and connected to the sleeve clutch member 169 by any suitable means 220. The base or web connecting the side arms of the yoke 218 is convex and provided with a cam groove 221 80 cooperating with a fixed stud 222 carried by the frame of the machine. By means of the mechanism described, the sleeve clutch member 169 is normally connected with the key 22, and upon depression of the total control key 22, is moved into engagement with the clutch member 168 for the total printing mechanism.

85 It is desirable to prevent an operation of the total control key 22 after an item entering operation has been begun by the depression of an amount key. For this purpose the amount keys 20 are provided with cam nodes 230 (Fig. 2) which cooperate with a latch 231 supported by arms 232 secured to the control shaft 180. When an amount key is depressed, the control shaft 180 and pin 206 (Fig. 6) are rocked in clockwise direction a sufficient distance to swing the upper end of a pawl 233 under the stud 211 on the total control key 22. The amount key 20 is held in this position by the temporary latch 170 (Fig. 2).

90 When the item control key 21 is depressed, the control shaft 180 is rocked to carry the latch 231 over projections 240 (Fig. 2) of amount keys 20 depressed and under projections 240 of amount keys not depressed and releases the motor for an item entering operation. As the cam 160 (Fig. 5) is rotated, it

reciprocates the link 163 to rock the key coupler, and through the link 177, to move the temporary latches 170 to their release positions. The projects 240 are held below the

- 5 path of travel of the latch 231 by the temporary latch 170, so that when these latches 170 are released at the beginning of an operation, the manipulative members 23 are permitted to rise to bring the projections 171 in front 10 of the latches 170 to permit the manipulative members 23 to move to normal positions when released by the latch 231. When the motor releasing mechanism is returned to home position, the pawl 233 is returned to home position 15 by a spring 241 connected thereto and to the total control key 22.

The total control key may be depressed after an item operation is completed or at any time when no amount keys are depressed. 20 When the total control key is depressed, it first connects the sleeve clutch member 169 with the clutch member 168 to drive the total printing mechanism. The control shaft 180 is then rocked to lock out all of the amount 25 keys. This movement of the control shaft rocks the pawl 233 over the stud 211 carried by the total control lever, holding the lever depressed until the total printing operation is completed. When this operation is completed, the total control lever will be released, and the clutch sleeve member 169 will be returned to home position by the spring 210.

The key members 23 are also provided with shoulders 250 for cooperation with fingers 35 251 pivoted on a cross channel bar frame 252 to prevent a simultaneous depression of a plurality of amount keys in the same denominational group.

An item of a transaction is entered in a 40 totalizer and printed on an issuing strip by first depressing amount keys 23 (Figs. 1A, 1B and 2) representing the value of the item and then subsequently depressing the item control key 21 (Figs. 1A and 5). After each 45 of the items of a transaction has been entered and printed, the total control key 22 (Figs. 1B and 6) is depressed to operate the total printing mechanism, which prints the total of the items involved below the items, feeds the printed total past a severing knife 125 (Fig. 7), and clears the totalizer to prepare it for a subsequent transaction.

While the form of mechanism herein shown and described is admirably adapted to fulfill 55 the objects primarily stated, it is to be understood that it is not intended to confine the invention to the one form or embodiment herein disclosed, for it is susceptible of embodiment in various forms all coming within 60 the scope of the claims which follow.

What is claimed is:—

1. In a machine of the class described, the combination with an item printing mechanism; a total printing mechanism; and a single driving means therefor; of shiftable

means to connect the driving means with the item printing mechanism or the total printing mechanism; the shiftable means normally in connection with one of said mechanism; and manipulative means to disconnect the shiftable means from the mechanism with which it is normally engaged and connect it with the remaining mechanism. 70

2. In a machine of the class described, the combination with accumulating mechanism; an item printing mechanism; and a total printing mechanism separate from the item printing mechanism, for accumulating individual items, and for listing such individual items, and printing a total of the accumulation 80 on a single receipt; of a drive means common thereto; a clutch mechanism interposed between the item printing mechanism and the total printing mechanism, and including driven members connected with the item printing mechanism and the total printing mechanisms, respectively, and a drive member engageable with either of the driven members of the clutch to actuate one or the other of the printing mechanisms alone; a manipulative means; a cam member connected with the drive member of the clutch and controlled by the manipulative means to shift the drive member in either direction, and means operating upon the cam member 90 to normally shift the drive member into engagement with that driven member of the clutch connected with one of the printing mechanisms. 95

3. In a machine of the class described, the combination with item printing mechanism; operating means therefor; separate total printing mechanism and operating means therefor; of driving means shiftable between the item printing operating means and the total printing operating means, but normally connected with the item printing operating means, a rockable member connected to the shiftable driving means; means operable at will to rock said member in one direction to shift the driving means to disconnect the driving means from the item printing operating means and connect it with the total printing operating means; and means to rock said member in the opposite direction to restore the driving means to connection with the item printing operating means. 110 115

4. In a machine of the class described, the combination with means to accumulate and print items; a main operating member 120 through which the accumulation and printing of items is effected; and total printing mechanism separate from the item printing mechanism; of a drive mechanism; means to hold the drive mechanism normally ineffective; means to normally connect the drive mechanism with the main operating member; and manipulative means to disconnect the drive mechanism from the main operating member, and connect it with the total 125 130 135

printing mechanism and to render the drive mechanism effective.

5. The combination of item printing mechanism; operating means therefor; separate total printing mechanism; operating means therefor; common means supporting both operating means; common driving means for both of said operating means for separately operating said printing mechanisms; a total printing control key; connections intermediate the total printing control key and the driving means, and operated by said key to connect the driving means with the operating means for the total printing mechanism; and means operating upon the total key to normally maintain the driving means connected to the operating means for the item printing mechanism.

6. The combination of item printing mechanism; operating means therefor; separate total printing mechanism; operating means therefor; common means supporting both operating means; common driving means for both of the operating means for separately operating the printing mechanisms, and normally in driving relation with the operating means for the item printing mechanism; a rockable and slidable member connected to the common driving means; and means operable at will to actuate said member to disconnect the driving means from the item printing operating means, and connect said driving means to the total printing operating means.

35. 7. The combination of item printing mechanism; operating means therefor; separate total printing mechanism; operating means therefor; common driving means for both of said operating means to separately operate said printing mechanisms; a stationary member; a shiftable device having a slot cooperating with the stationary member; a manually operable member; and means intermediate the manually operable member and the shiftable device to move the latter to shift the common driving means, through the cooperation of the slot and stationary member, from its connection with the item printing operating means into connection with the total printing operating means.

In testimony whereof I affix my signature.
EDWARD J. VON PEIN.

CERTIFICATE OF CORRECTION.

Patent No. 1,824,248.

Granted September 22, 1931, to

EDWARD J. VON PEIN.

It is hereby certified that error appears in the printed specification of the above numbered patent requiring correction as follows: Page 4, line 37, for the word "catch" second occurrence read trip; page 5, line 103, claim 3, after "mechanism" insert a semi-colon; line 108, strike out the comma after "means" and insert a semi-colon; line 113, after "means" insert a comma, and line 114, after the word "to" insert the word automatically; page 6, line 1, claim 4, after "mechanism" insert a comma; and that the said Letters Patent should be read with these corrections therein that the same may conform to the record of the case in the Patent Office.

Signed and sealed this 3rd day of November, A. D. 1931.

(Seal)

M. J. Moore,
Acting Commissioner of Patents.
